STAPLING MACHINE

Lyman B. Cook, Riverton, and Henry J. Gerke, Jr.,
West Collingswood, N. J., assignors to Acme
Staple Company, Camden, N. J., a corporation
of New Jersey

Application May 25, 1940, Serial No. 337,234

7 Claims. (Cl. 1-3)

This invention relates to improvements in stapling machines of the general class wherein the work to be stapled is placed between two normally separated work-engaging parts one of which is carried by the stationary frame of the machine and one of which is carried by a member which is movably mounted on the frame and operable to move one of said parts toward the other; and wherein the staple guide and staple driver is associated with or carried by one of said parts, and the staple clinching anvil is associated with or carried by the other of said parts. During the operation of the several types of machines of this general class, the said member is first operated to move its work-engaging part toward the work-engaging part of the frame, and, thereafter, the staple driver is operated to drive the staple through the work and against the clinching anvil to clinch the staple legs.

The object of the present invention is to provide machines of the aforesaid general class with novel and advantageous mechanism wherein folding devices in co-operation with the aforesaid work-engaging parts will produce folds in the work to be stapled, and wherein staples will be driven through the folds thus produced and set in the work to hold the folds in place.

The invention resides in the elements and the combinations of them in the improved machine as will be hereinafter described and claimed.

In the accompanying drawings, illustrating the invention,

Figure 1 is a side view of a stapling machine showing one form of embodiment of the invention.

Figure 2 is a top view of the forward end of the machine, showing the folding devices carried thereby and the stop for positioning the work.

Figure 3 is a vertical section of the forward end of the frame, the forward end of the movable member, and the parts carried by the frame and the member.

Figure 4 is a vertical section on line 4-4 of Fig. 3.

Figure 5 is a front view of parts of the machine, showing the folding devices in one position thereof during the folding of the work.

Figure 6 is a view similar to Fig. 5, showing the folding devices in the final position thereof and the work completely folded.

Figure 7 is a front view of a piece of work having a series of successive folds produced therein and stapled by the machine.

Figure 8 is a sectional detail of the folded and stapled work, on line 8-8 of Fig. 7.

The particular type of stapling machine which

is illustrated herein as forming a part of the present improvements is shown and described in Letters Patent No. 1,919,944, dated July 25, 1933, to which reference may be had.

Referring to the aforesaid drawings, 2 designates the upper portion of the frame of the machine which in its complete state may be like the frame illustrated in the said Letters Patent.

The frame 2 is provided with a forwardly extending arm 5 adapted to receive and support the work to be stapled.

The frame arm 5 is provided with a staple magazine 6 having a staple guiding bar 9 for receiving and guiding the staples 7 into a vertically extending channel or guide 11 which is formed between two plates 12 and 14 which are secured to the forward end of the arm 5 and form, in effect, a part of the arm.

The row of staples 7 is fed forwardly toward and against the rearward surface of the plate 12 in the usual manner by a suitable follower.

The foremost staple of the row thereof occupies a position within the staple guide 11 and directly above a plate-like staple driver 34 which is adapted to be reciprocated vertically within the staple guide 11 and to act against the staples successively and drive them upwardly through the guide.

Each time the staple driver 34 is moved upwardly through the guide 11 it drives the foremost staple 7 upwardly through the guide, and each time the driver 34 is moved downwardly to the position shown in the drawings, after a staple driving operation, the row of staples is fed forwardly and the foremost staple enters the guide 11.

The frame 2 is provided with an upwardly extending lug 35 having a member 36 pivoted thereto, at 37. This member 36 extends forwardly from its pivot and over the frame arm 5 and has a downwardly-directed staple clinching anvil 64 secured to the forward end portion thereof.

The member 36 is movable on its pivot 37 to lower and raise the anvil 64 and when the member 36 is lowered the anvil 64 is brought into proper operative relation to the staple guide 11 and staple driver 34.

The forward end of an arm 41 is pivoted, at 42, to the forward portion of the member 36, and the rearward end of the arm 41 embraces a lug 43, 50 rising from the rearward portion of the member 36, by a pin or bolt 44 carried by the arm 41 and extending through a slot 45 in the lug 43. A spring-pressed pin 47 urges the pin or bolt 44 toward the upper end of the slot 45 and serves as a 55

yieldable means for supporting the rearward end of the arm 41.

Pivoted, at 50, to the arm 41 is the upper end portion of an operating part 51, the lower end of which is connected to a downwardly extending operation bar 53 forming a continuation of the part 51.

The part 51 and bar 53, and therewith the arm 41 and member 36, are urged to and yieldably supported in the raised position shown in Figs. 1, 3 and 4, by a suitable spring like the spring illustrated and described in said Letters Patent.

The machine is operated by the lowering and raising of the bar 53 and part 51, and for this purpose the bar 53 may be connected to a suitable pedal for the operation of the machine by foot power or the bar 53 may be moved downwardly by any other suitable means.

The staple driver 34 is operated by a lever 58 fulcrumed in the frame arm 5 and resting normally in the position shown in Fig. 1 by the weight of the forward portion thereof. The forward end of the lever 58 is provided with a pin 60 which extends through a hole in the staple driver 34. The rearward end portion of the lever 58 is located between a lug 61 on the part 51 and a screw 62 screwed into and through a lug 63 projecting from the part 51.

When the bar 53 and part 51 are moved downwardly to operate the machine, the part 51 first operates the arm 41 to lower the staple clinching anvil 64, and, thereafter the screw 62 engages the lever 58 and moves the rearward end thereof downwardly, and thereby moves the forward end 35 of the lever and therewith the staple driver 34 upwardly to drive and set a staple in the work.

Excepting some modification of the staple clinching anvil and the manner of securing it to the member 36, the construction and operation 40 of the parts of the machine thus far described are the same as illustrated and described in the aforesaid Letters Patent.

The staple clinching anvil 64 is secured within a groove in block 65 having a stem 66 which is set 45 in an opening in the member 36 and secured thereto by a transverse pin 67 which extends through the stem and member. The anvil 64 has a groove therein suitably formed to receive the staple legs and direct them toward each other 50 during the staple driving and clinching operation.

The block 65 forms, in effect, a part of the member 36, and the bottom wall 68 of the block constitutes a work-engaging part above a work-engaging part 69 formed by the top wall of the 55 arm 5 of the machine frame, the top walls of the frame plates 12 and 14 and the top wall of a bracket 70 secured to the frame plate 12 and extending forwardly therefrom.

The work-engaging parts 69 and 70 of the 60 member 36 and the machine frame, respectively, are constructed to receive the work to be stapled between them. Such parts are constructed and related to work folding devices to co-operate therewith to effect the folding of the work during 65 the operation of the machine; and we shall now describe the said work folding devices.

The frame plate 12 is provided with lugs 71, 71 which extend outwardly from the respective sides thereof. These lugs 71, 71 support two oppositely disposed levers 72, 72 which embrace the lugs 71, 71 and which are fulcrumed thereon at 73, 73. These levers 72, 72 have upper arms 74, 74 which extend inwardly and upwardly from the lever fulcrums 73, 73; and they have lower arms 75, 75 which extend downwardly from the lever

fulcrums and which are connected by a spring 76 which tends to draw the arms 75, 75 toward each other. The lever arms 75, 75 are provided with stop projections 77, 77 which engage the sides of the frame plate 12 and limit the inward movement of the arms 75, 75. The spring 76 holds the levers 72, 72 yieldably in the normal position shown in Fig. 4, and it permits the lever arms 74, 74 to be depressed and returns them to the normal position after being depressed and released.

Each lever 72, 72 is formed sheet metal and comprises similarly shaped front and back plates which are connected by a web 78, 78 as clearly shown in the drawings. The upper lever arms 15 74, 74 are constructed and arranged to operate between the work-engaging parts 68 and 69 of the member 36 and frame arm 5, and the arms 74, 74 are bifurcated to embrace the staple guide 11 and the path of the staple when the latter is 20 driven upwardly and the arms 74, 74 are depressed from the position shown in Fig. 4 to the position shown in Fig. 6, during the operation of the machine, as presently described.

Arranged to operate between the work-engaging parts 68 and 69 of the member 36 and frame arm 5, and between the upper lever arms 74, 74 is a centrally disposed folding plate or blade 79 carried by the lower end of a stem 80 which rises therefrom. The stem 80 is slideable within and 30 guided by a cylinder or tube 81 whose lower end is secured upon a plate or bracket 82 which extends forwardly from the forward end of the member 36, the plate 82 being secured to the member 36 between the same and the anvil block 35 65.

The stem 80 has a reduced upper portion 83 which is threaded for the reception of a nut 84 which rests upon the top of the tube 81 and has 40 a collar 85 which is formed thereon and which extends down into the tube. A spring 86 encircles the upper end portion 83 of the stem and acts between the top of the lower portion of the stem 80 and an inwardly extending flange 87 on the upper end of the tube 81 and urges the stem 45 80 and folding blade 79 downwardly. By turning the nut 84, the stem 80 and therewith the folding blade 79 may be raised or lowered with respect to the member 36. A lock nut 88 is screwed on to the upper end of the reduced portion 83 of the 50 stem 80 to engage the nut 84 and lock it in different positions of adjustment.

The folding blade 79 extends forwardly from the stem 80 and is provided with an upwardly projecting pin 89 fitted to slide within a hole in 55 the plate 82 and prevent the stem and blade from turning on the axis of the stem; and the block 65 has a slot 90 formed therein for the reception of the rearward end portion of the folding blade 79 when the member 36 is moved downwardly 60 with respect to the blade, during the operation of the folding devices hereinafter described.

A stop plate 91 is provided rearwardly of the folding devices to be engaged by the work to be folded to position the same with respect to the 65 folding devices. This plate 91 is carried by a bracket 92 which is slideable on the frame arm 5 and constructed to be held in different positions of adjustment by a set screw 93 screwed into one side of the bracket and engaging the frame arm 5. 70

The work to be folded and stapled is indicated at 94 in Figs. 1, 3, 4, 5 and 6. This work may be any suitable foldable material, such, for example, as leather and fabric; and the work may be folded and stapled for any desired purpose, such, for 75

example, as pleating or ruffling of an edge portion of the fabric or material used in forming the body portions of hand bags.

The work 94 to be folded and stapled is placed upon the lever arms 74, 74 beneath the folding blade 79 and between the work-engaging parts 68 and 69, of the member 36 and frame arm 5, respectively, with the rearward edge of the work resting in close proximity to or in contact with the stop plate 91. The operating part 51 is then moved downwardly by foot, hand or other power. During the initial downward movement of the operating part 51, it moves the anvil carrying member 36 and arm 41 downwardly as a unit and causes the downwardly extending rearward end portion of the folding blade 79 to press the work 94 beneath it downwardly between the inner ends of the lever arms 74, 74 and press the work into V-form until the bottom 68 of the work-engaging part or block 65 of the member 36 engages the work 94 and forces it downwardly upon the free ends of the lever arms 74, 74 and begins to force said arms downwardly and the lever arms 75, 75 outwardly against the action of the spring 76, as shown in Fig. 5. As the continued downward movement of part 51 continues the downward movement of the member 36, the lever arms 74, 74 continue to move inwardly and the downward movement of the blade 79 is stopped by the work 94 beneath it engaging the work-engaging part 69 of the frame arm 5. After the downward movement of the block 79 is thus stopped, the member 36 continues to move downwardly to move the parts operated thereby to the position shown in Fig. 6, during which the sides of the V-formation of the work, shown in Fig. 5, are forced inwardly by the free ends of the lever arms 74, 74, and such sides are buckled outwardly into the pleat formation of the work, shown in Fig. 6, while the member 36 moves the blade 79 and the lever arms 74, 74 to the position shown in Fig. 6. When the parts reach this position, the folded work 94 with the free end portions of the lever arms 74, 74 embraced by folds of the work, are pressed downwardly upon the work-engaging part 69 of the frame arm 5 by the work-engaging part 68 of the member 36, thereby stopping the further downward movement of the member. When the parts reach the position shown in Fig. 6, the rearward end of the folding blade 79 is forwardly of but in close proximity to the staple guiding channel 11, and the bifurcated free ends of the lever arms 74, 74 embrace the sides of the staple guiding channel 11, and the staple clinching anvil is directly over the staple guiding channel. Now, the continued downward movement of the operating part 51 moves the arm 41 downwardly against the yielding spring-pressed pin 47 and causes the screw 62 carried by the part 51 to operate the lever 58 to move the staple driver 34 upwardly and thereby drive the foremost staple 1 of the row thereof upwardly through the staple guiding channel 11 and through the folds of the work and into the clinching groove of the anvil 64 which clinches the staple legs upon the work and completes the setting of the staple in the folded work as shown in Figs. 7 and 8. This done, the operating part 51 is raised to raise the member 36 and parts carried thereby, and to permit the spring 76 to return the levers 72, 72 to the normal position, shown in Figs. 1, 3 and 4, for a succeeding work folding and stapling operation.

When it is desired to produce a series of successive folds or pleats in the work, as shown in

Figs. 7 and 8, the operative moves the work laterally over the lever arms 74, 74 the proper distance for the desired spacing of the pleats or folds after each folding and stapling operation.

We claim as our invention:

1. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, folding devices located between and associated with said work-engaging parts and co-operating therewith to produce folds in the work to be stapled when the work-engaging part of the member is lowered toward the work-engaging part of the frame, a staple driver, and means operable to lower said member and its work-engaging part toward the work-engaging part of the frame and thereafter operable to actuate said driver to drive a staple through said guiding means and through the folds of the work and clinch it against said anvil.

2. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, two laterally spaced, downwardly and inwardly movable work-folding arms yieldably mounted on the frame and operating between said work-engaging parts, a centrally disposed folding blade yieldably carried by said member and positioned to enter and leave the space between said arms when said member is lowered and raised, whereby said arms and said blade in co-operation with said work-engaging parts will produce folds in the work to be stapled when said member is lowered, a staple driver, and means operable to lower said member and its work-engaging part toward the work-engaging part of the frame and thereafter operable to actuate said driver to drive a staple through said guiding means and through the folds of the work and clinch it against said anvil.

3. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, two laterally spaced levers fulcrumed on the frame and having downwardly and inwardly movable, work-folding upper arms operating between said work-engaging parts, said levers having lower arms extending downwardly from the fulcrums thereof, a spring connecting said lower arms and yieldably urging said upper arms to a raised position, a centrally disposed folding blade yieldingly carried by said member and positioned to enter and leave the space between said upper arms when said member is lowered and raised, whereby said upper arms and said blade in co-operation with said work-engaging parts will produce folds in the work to be stapled when said member is lowered, a staple driver, and means operable to lower said member and its work-engaging part toward the work-engaging part of the frame and thereafter operable to actuate said driver to drive a staple through said guiding means and through the folds of the work and clinch it against said anvil.

folds of the work and clinch it against said anvil.

4. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, two laterally spaced, downwardly and inwardly movable work-folding arms yieldably mounted on the frame and operating between said work-engaging parts, a centrally disposed folding blade carried by a stem rising therefrom and slidable in a part carried by said member, permitting the blade to be raised and lowered with respect to the member, a spring yieldably urging said blade to a lowered position with respect to the member, said blade being positioned to enter and leave the space between said arms when said member is lowered and raised, whereby said arms and said blade in co-operation with said work-engaging parts will produce folds in the work to be stapled when said member is lowered, a staple driver, and means operable to lower said member and its work-engaging part toward the work-engaging part of the frame and thereafter operable to actuate said driver to drive a staple through said guiding means and through the folds of the work and clinch it against said anvil.
5. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, two laterally spaced levers fulcrumed on the frame and having downwardly and inwardly movable, work-folding upper arms operating between said work-engaging parts, said levers having lower arms extending downwardly from the fulcrums thereof, a spring connecting said lower arms and yieldably urging said upper arms to a raised position, a centrally disposed folding blade carried by a stem rising therefrom and slidable in a part carried by said member, permitting the blade to be raised and lowered with respect to the member, a spring yieldably urging said blade to a lowered position with respect to the member, said blade being positioned to enter and leave the space between said arms when said member is lowered and raised, whereby said arms and said blade in co-operation with said work-engaging parts will produce folds in the work to be stapled when said member is lowered, a staple driver, and means operable to lower said member and its work-engaging part toward the work-engaging part of the frame and thereafter operable to actuate said driver to drive a staple through said guiding means and through the folds of the work and clinch it against said anvil.

the folds of the work and clinch it against said anvil.

6. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, two laterally spaced, downwardly and inwardly movable work-folding arms yieldably mounted on the frame and operating between said work-engaging parts, a centrally disposed folding blade yieldably carried by said member and positioned to enter and leave the space between said arms when said member is lowered and raised, whereby said arms and said blade in co-operation with said work-engaging parts will produce folds in the work to be stapled when said member is lowered, a staple driver, and means operable to lower said member and its work-engaging part toward the work-engaging part of the frame and thereafter operable to actuate said driver to drive a staple through said guiding means and through the folds of the work and clinch it against said anvil, said arms being bifurcated to embrace the path of the staple driven by said driver.

7. In a stapling machine, the combination of a frame having staple guiding means and a work-engaging part, a member movably mounted on the frame and having a staple-clinching anvil and a work-engaging part above the work-engaging part of the frame, said work-engaging parts being adapted to receive the work to be stapled between them, two laterally spaced levers fulcrumed on the frame and having downwardly and inwardly movable, work-folding upper arms operating between said work-engaging parts, said levers having lower arms extending downwardly from the fulcrums thereof, a spring connecting said lower arms and yieldably urging said upper arms to a raised position, a centrally disposed folding blade yieldingly carried by said member and positioned to enter and leave the space between said upper arms when said member is lowered and raised, whereby said upper arms and said blade in co-operation with said work-engaging parts will produce folds in the work to be stapled when said member is lowered, a staple driver, and means operable to lower said member and its work-engaging part toward the work-engaging part of the frame and thereafter operable to actuate said driver to drive a staple through said guiding means and through the folds of the work and clinch it against said anvil, said upper arms being bifurcated to embrace the path of the staple driven by said driver.

LYMAN B. COOK.
